(57) **CLAIM**

The ornamental design for a footwear bottom, as shown and described.

DESCRIPTION

FIG. 1 is a perspective view of a footwear bottom showing our new design;

FIG. 2 is a bottom plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The broken line in the figures is for illustrative purposes only and forms no part of the claimed design.

For clarity, the unclaimed shoe upper has been omitted from FIGS. 2-6, leaving the arrangement and placement of the features comprising the claimed design.
